UNITED STATES PATENT OFFICE.

FRANK E. CLARK, OF HARMONY TOWNSHIP, CHAUTAUQUA COUNTY, NEW YORK.

PROCESS FOR MAKING BELTS.

1,286,229.

Specification of Letters Patent.

Patented Dec. 3, 1918.

Application filed November 12, 1917. Serial No. 201,681.

To all whom it may concern:

Be it known that I, FRANK E. CLARK, a citizen of the United States, and a resident of Harmony township, in the county of 5 Chautauqua and State of New York, have invented new and useful Improvements in Processes for Making Belts, of which the following is a specification.

My invention relates to a process for 10 making belts and has particular reference to a process employed in the making of composite belts, although not restricted to this particular class of belts.

An important object is to provide a process 15 by which a belt, constructed in accordance therewith, will possess a uniform coefficient of expansion throughout the entire length of the same.

A further object is to provide a process 20 in which the various steps taken in the carrying out of the same will be so related as to render the result of each subsequent step dependent upon the performance of the preceding one in order to attain the ultimately 25 desired object.

A further object is to provide a process 30 wherein the various steps involved therein may be efficiently performed by the average person unskilled in the art to which the process appertains.

Other advantages and objects of the process will be apparent during the course 35 of the following description.

In the accompanying drawings forming a 40 part of this specification and in which like numerals are employed to designate like parts throughout the same.

Figure 1 shows a stretching device embodying the invention,

Fig. 2 shows a device similar to that of Fig. 1 to be used in connection with the same,

Fig. 3 is a plan view of Fig. 1,

Fig. 4 is a detail view of a portion of the device shown in Fig. 1, and,

Fig. 5 is a vertical, longitudinal, sectional view of a cylinder.

In the drawings wherein for the purpose of illustration is shown a preferred form of 45 my invention the numeral 10 indicates a ceiling from which the device is preferably suspended. While I have shown my device as being suspended from the ceiling I wish it understood, however, that any other suitable means of support for the same may be

employed. To suitable supports 11, 12, 13 and 14 there are journaled pulleys 15, 16, 17 and 18, respectively.

In proximity to the pulleys 15 and 16 there is suspended by any suitable means of 50 support an elongated cylinder 19 having mounted therein a reciprocatory piston 20. This piston is preferably formed of a hollow pipe, the outer diameter of which is substantially less than the inner diameter of 55 the cylinder 19. Should it be desired, however, the piston may be solid, I having employed a hollow piston in order to obtain a structure as light in weight as possible and to further enable me to employ the least 60 amount of fluid possible used in the actuation of the same as will hereinafter be described.

It is to be noted that the end of the piston 20 confined within the cylinder 19 is 65 closed by means of a suitable screw-threaded plug or cap 21. Upon one end of the cylinder 19 there is mounted a screw-threaded cap 22, as shown, while the other end of the cylinder is provided with a screw-threaded stuffing-box 23 carrying a flange 24 adapted to receive thereon a flange 25 carried by a gland 26, the gland 26 being designed to occupy a portion of the space 70 afforded between the stuffing-box 23 and the piston 20 passing therethrough as clearly 75 shown in Fig. 5.

Within a track or guide 27 suspended in proximity to the cylinder 19 and extending 80 in the direction of travel of the piston 20, there is slidably carried a carriage 28 having 85 journaled thereto a pulley 29.

A fluid pressure pipe 30 communicating 90 a suitable supply of pressure, not shown, with the interior of the cylinder 19, is employed whereby pressure is supplied to the cylinder 19 for actuation of the piston 20. At a suitable point upon the fluid pressure pipe 30 there is disposed a pressure regulating valve 31 of the conventional form 95 or type, this valve being provided to allow a predetermined pressure to be built up within the cylinder 19, this pressure being predetermined by means of the regulating rod 32 of the valve 31. To the pipe 30 at a suitable 100 point between the valve 31 and the cylinder 19 there is connected a pressure relief or safety valve 33 by means of a suitable connection, as shown at 34. This pressure relief or safety valve is of the conventional 105 110

type and provided with means, as indicated at 35, whereby the point at which the same will be actuated may be predetermined or regulated. To the valve 33 there is connected a discharge pipe 36, this discharge pipe being provided as a means for conveying spent fluid to any desired or remote location. To the cylinder 19 or to the fluid pressure pipe 30 at a suitable point between the cylinder 19 and valve 31 there is connected a discharge pipe 37 having a manually operated valve 38 disposed therein, the discharge pipe 37 being connected to a suitable ejector or exhaust pump as shown at 39. To the exhaust pump 39 there is connected a pipe 39' by which fluid exhausted from the cylinder 19 by the pump may be conveyed to any desired or remote point. If sufficient discharge head is available the pump 39 may be omitted.

The above description is common to the disclosures shown in Figs. 1 to 5 inclusive, while in Fig. 2 it is to be noted that I have dispensed with the pulley 18 and have substituted therefor, pulleys 40, 41, 42 and 43, the pulleys 40, 41, 42 and 43 being journaled to vertical supports 44 and 45, respectively. It is to be further noted that in Fig. 2 there is shown disposed approximately intermediate the pulleys 41 and 43 a press 46' the function of which will hereinafter be described.

In use the operation of the device is as follows: In construction a belt the base element comprising a strip of cotton, canvas, or any other flexible material which may be used in the construction of a composite belt, is placed upon the pulleys as shown in Fig. 1, the ends of the same being secured together by any suitable means, as a hook or the like.

Assuming that the valve 38 is closed the pressure relief or safety valve 33 is set at a desired point of actuation. The pressure regulating valve 31 is set also at a desired point corresponding to that of the valve 33. The valve 31' disposed within the fluid pressure pipe 30 is then gradually opened permitting fluid pressure to pass through the pipe 30 and into the cylinder 19 whereupon the piston 20 is actuated moving the carriage 28 carrying the pulley 29. The action of the piston 20, indirectly through the carriage 28 and pulley 29, upon the flexible material 46 sets up a tension within the flexible element 46 the degree of tension corresponding directly to the actuation point of valves 31 and 33. During this time power is applied to the pulley 47 causing the flexible material to travel in the direction indicated by the arrows. A suitable sizing material is then applied to the flexible material in its course of travel a sufficient length of time to impregnate the pores of the material therewith. The action created by the sizing material causes the expansion of the flexible material,

whereupon the pressure exerted within the cylinder 19 is momentarily lowered. The lowering of this pressure affects the actuation of the pressure regulating valve 31, thereby supplying additional pressure within the cylinder 19 thus maintaining the normal pressure within the cylinder. The flexible material 46 is allowed to remain in the position as indicated in Fig. 1 for a period of from ten to fourteen hours during which period a relatively slow but constant travel in the direction of the arrows is maintained. As the flexible material 46 dries in this travel it necessarily contracts thereby continuing to set up an excessive pressure within the cylinder 19, which excessive pressure is released therefrom by means of the relief valve 33. While I have described this step in the process of building up a belt by my proposed method as being accomplished with one cylinder it is obvious that a plurality of cylinders may be employed functioning in the same manner.

When the flexible material has become completely dry it is removed from the pulleys shown in Fig. 1 and placed upon the pulleys as indicated in Fig. 2. The pressure regulating means is employed in the same manner as hereinbefore described to maintain a constant tension within the flexible material 46. The flexible material 46 is then moved by any suitable means along its course of travel in the direction of the arrows. At a point A in proximity to the press 46' a suitable adhesive is applied to either one of both or both sides of the flexible material, as desired. A facing of leather, rubber or other suitable material is then applied to either one of both or both sides of the flexible material as the case may be. The flexible material carrying the facing material and adhesive is then passed into the press 46' whereupon pressure is applied for a desired length of time thereby necessarily adhering the facing material to the flexible base material comprising the belt. The pressure is then released from the press whereupon the flexible material carrying the adhered facing material is moved in the course of travel indicated by the arrows. The application of suitable adhesive and facing material is continued until the entire length of flexible material has undergone the above described operations. The dampening effect of the adhesive upon the flexible material tends to cause the same to expand. This expansion is compensated by the action of the fluid pressure within the cylinder 19 in the manner as hereinbefore described in connection with Fig. 1. After the flexible material has been faced with a suitable material as described it is allowed to remain in the position shown in Fig. 2 for a period varying from ten to fourteen hours during which time the uniform tension is maintained within

the same by the action of the fluid pressure within the cylinder 19 as hereinbefore described in connection with Fig. 2.

When it is desired to remove the flexible material 46 from the position shown in Fig. 1 or the finished product as indicated in Fig. 2, the valve 31' of the fluid pressure pipe 30 is closed. The valve 38 of the discharge pipe 37 is then opened and the use of the 10 ejector or exhaust pump 39 is involved thereby releasing or ejecting the contents of the cylinder 19 which tends to create a partial vacuum within the cylinder 19, thereby causing the piston 20 to move to the position 15 shown in Fig. 5 thus relieving the tension maintained within the flexible elements 46 or the finished product as the case may be, and permitting easy removal of either the flexible material or finished product from their 20 respective positions, whereupon other material, in either instance may be inserted to be operated upon.

It is to be understood that various changes in the shape, size and arrangement of parts 25 may be resorted to without departing from the spirit of my invention or the scope of the subjoined claims.

Having thus described my invention, what 30 I claim as new and desire to secure and protect by Letters Patent of the United States, is:

1. A process for making belts consisting of applying a suitable sizing solution to flexible material, allowing said sizing material 35 to dry thereupon, subjecting said flexible material to a constant tension while said sizing material is drying thereupon, and positively driving said flexible material in an endless path during the drying period of 40 the sizing solution to uniformly distribute the constant tension throughout the length of the flexible material.

2. A process for making belts consisting of applying a suitable sizing solution to 45 flexible material, allowing said sizing material to dry thereupon, subjecting said flexible material to a constant tension while said sizing material is drying thereupon, and positively driving said flexible material at a 50 constant rate of speed in an endless path during the drying period of said sizing

solution to uniformly distribute the constant tension throughout the length of the flexible material.

3. A process for making belts consisting of applying a suitable sizing solution to 55 flexible material, allowing said sizing material to dry thereupon, subjecting said flexible material to a constant tension while said sizing material is drying thereupon, positively 60 driving said flexible material at a constant rate of speed in an endless path during the drying period of the sizing solution to uniformly distribute the constant tension throughout the length of the flexible 65 material, applying an adhesive material to said flexible material, adhering facing material to said flexible material by means of said adhesive material.

4. A process for making belts consisting of applying a suitable sizing solution to 70 flexible material, allowing said sizing material to dry thereupon, subjecting said flexible material to a constant tension while said sizing material is drying thereupon, 75 positively driving said flexible material in an endless path during the drying period of the sizing solution to uniformly distribute the constant tension throughout the length of the flexible material, applying an 80 adhesive material to said flexible material, adhering facing material to said flexible material by means of said adhesive material, subjecting said flexible material together with said adhesive material and facing material to pressure, subjecting said flexible material together with said facing material and adhesive material to a constant and uniform tension, said tension being maintained 85 during a drying period of said adhesive 90 material.

5. A process for making belts consisting of subjecting flexible material to constant tension, applying an adhesive material to 95 said flexible material, positively driving said treated flexible material in an endless path, adhering facing material to said flexible material, subjecting said flexible material to a constant tension while said adhesive material is drying thereupon.

FRANK E. CLARK.
